PRINTING-PRESS.

1,111,666.

Specification of Letters Patent. Patented Sept. 22, 1914.

Application filed December 15, 1911. Serial No. 665,917.

To all whom it may concern:

Be it known that I, ROBERT MIEHLE, a citizen of the United States, residing at Chicago, in the county of Cook and State 5 of Illinois, have invented a certain new and useful Improvement in Printing-Presses, of which the following is a full, clear, concise, and exact description, reference being had to the accompanying drawings, forming a 10 part of this specification.

My invention relates to printing presses and has for its object the provision of an improved printing press inking mechanism whereby the distributing rollers may readily 15 be displaced from the inking rollers in order to gain access to the inking rollers for removing, replacing and cleaning the same.

My invention will be best understood by a 20 description of the preferred embodiment thereof shown in the accompanying drawing in which—

Figure 1 is a side view of so much of a printing press, equipped in accordance with my invention, as is necessary to an understanding of the invention, the distributing rollers being shown in engagement with the inking rollers; Fig. 2 is a view similar to Fig. 1 with the exception that the distributing rollers have been withdrawn from the 25 inking rollers; Fig. 3 is a view similar to Figs. 1 and 2 excepting that the distributing rollers are shown in Fig. 3 as being only partially withdrawn from the inking rollers; and Fig. 4 is a plan view of the equipment as it is illustrated in Fig. 2.

Like parts are indicated by similar characters of reference throughout the different figures.

The particular type of printing press 40 illustrated is a flat bed press to which, however, the invention is not to be limited, nor is the invention to be limited to a press in which made up forms are employed since the character of the printing surface is 45 immaterial.

As the invention is illustrated, the press bed 1 is adapted to reciprocate beneath the impression cylinder 2. Inking or form rollers 3, 3¹, 3², 3³ engage the printing surface 50 for the purpose of inking the same in a manner well known by those skilled in the art, though I do not limit myself to the direct contact with the printing surface of all of

the inking rollers that are supplied by the distributing roller.

Two distributing rollers 4, 4¹, which distributing rollers are also driving rollers, engage the inking rollers as illustrated for the purpose of turning the same and supplying ink to the inking rollers as they are turned. 60 The distributing rollers are provided with pinions 5 that engage pinions 6 which in turn are in mesh with a rack 7 secured to the press bed, whereby the various rollers are turned as the press bed reciprocates. The 65 inking mechanism is also provided with the usual rider rollers 8 which engage the driving or distributing rollers 4, 4¹, all as is well understood by those skilled in the art.

The inking or form rollers are journaled 70 in the usual adjustable bearings secured to the press frame 10. The distributing rollers 4, 4¹, the rider rollers 8, 8 and an extra distributing roller 9 are journaled upon a carriage 11. This carriage is journaled at its 75 upper end upon a shaft 12 whereby the carriage is swingingly mounted, the end of the carriage complementary to the end journaled upon the shaft 12 being free to rise and fall when the carriage is moved away from the 80 inking rollers, the bodily movement of the carriage and the rollers it carries being in a direction generally horizontal toward and away from the inking rollers. The shaft 12 is provided with a pinion 13 and some suitable means for turning it, such as a hand crank 14.

The pinion 13 engages a rack 15 secured to the press frame 10, the rack and pinion being disposed transversely with respect to the rollers whereby the rollers immediately supported upon the carriage are adapted to be moved toward and from the inking rollers as the pinion 13 is caused to move upon the rack 15 by the operation of the hand crank 14. The inner end of the 95 rack 15 is curved downward whereby the carriage 11 is raised at its pinion end (the end where the shaft 12 is located) when the carriage is bodily moved away from the inking rollers and is lowered when the carriage is brought into position to enable the distributing rollers to engage the inking rollers.

Guiding supports 16, 16¹ are adapted to engage the carriage when the carriage is in normal position, these guiding supports 100 serving to prevent the free end of the car-

riage from dropping when the inking rollers are absent and the carriage is in its normal position as illustrated in Fig. 1. The pinion end of the carriage is held in a depressed position, when such carriage is in the normal location illustrated in Fig. 1, by means of a detent 14¹ engaging the handle of the crank 14, the pinion 13 and the outer or pinion end of the carriage 11 being thus firmly held in a depressed position. The free end of the carriage 11 is provided with a sloping or cam surface 17 that is engaged with a sloping cam element 18 provided upon the printing surface supporting element, 10, the element 10 supporting the reciprocating form bed that presents a printing surface of one character to the impression cylinder portion, to which arrangement I do not limit myself. The elements 17 and 18 coöperate to depress the free end of the carriage 11 when the carriage is restored to normal or working position as illustrated in Fig. 1.

When the carriage is withdrawn so as to clear the inking rollers, the free end of the carriage rises and falls as the distributing rollers pass over the inking rollers, a result which also occurs when the carriage is restored to normal position if the inking rollers are present. If the inking rollers are absent when the carriage is restored, such carriage will ride upon the guiding supports 16 so that the undue depression of the carriage will not be permitted.

In the preferred construction, the pinion 13 is provided with a shoulder 20 which bears or rolls on the track 19. The pinion 13 is held in mesh with the rack 15 by the lower surface 21 of the rack and the stud 22 moving along the surface 21 and engaging the same as the carriage is moved. The stud 22 is mounted upon the carriage extension 23. I prefer to duplicate the elements 13 and 15 and the parts coöperating therewith, the opposite sides of the press having similar structures symmetrically related. In Fig. 4 I have shown one of these structures upon one side of the press. The presence of the duplicated structure upon the other side of the press will be readily understood.

It will be seen that when the parts are in the position illustrated in Fig. 1, the pinion end of the carriage is held down by the locking device 14¹ and that the opposite end of the carriage is held down by the elements 17 and 18 whereby all the rollers are in proper coöperative relation. When the locking device 14¹ is released and the pinion 13 is turned in a counterclockwise direction, such pinion will roll upwardly over the curved part of the rack 15 and lift the distributing roller 4 bodily over the inking roller 3 and the roller 4¹ will revolve over the roller 3².

Upon continuation of the operation of the

crank 14 the carriage will be drawn clear of the inking rollers, the carriage being supported in this withdrawn position by the shoulder 20 on track 19 and supports 16¹ engaging the free end of the carriage. 70

While I have herein shown and particularly described the preferred embodiment of my invention, I do not wish to be limited to the precise details of construction shown as changes may readily be made 75 without departing from the spirit of my invention.

Having thus described my invention, I claim as new and desire to secure by Letters Patent the following:— 80

1. A printing press having an inking roller for the printing surface of the press; a distributing roller for contacting with the inking roller; a carriage in which the distributing roller is mounted and which carriage is bodily movable toward and from the inking roller and is swingingly mounted at one end, said carriage being free to rise and fall at its opposite end as it is bodily removed; and means for holding the latter 90 carriage end in position when the distributing roller engages the inking roller.

2. A printing press having an inking roller for the printing surface of the press; a distributing roller for contacting with the inking roller; a carriage in which the distributing roller is mounted and which carriage is bodily movable toward and from the inking roller and is swingingly mounted at one end, said carriage being free to rise and 100 fall at its opposite end as it is bodily moved.

3. A printing press having an inking roller for the printing surface of the press; a distributing roller for contacting with the inking roller; a carriage in which the distributing roller is mounted and which carriage is bodily movable toward and from the inking roller and is swingingly mounted at one end, said carriage being free to rise and fall at its opposite end as it is bodily moved; means for holding the latter carriage end in position when the distributing roller engages the inking roller; and a guiding support for guiding the carriage in its bodily movement in the absence of the inking roller. 115

4. A printing press having an inking roller for the printing surface of the press; a distributing roller for contacting with the inking roller; a carriage in which the distributing roller is mounted and which carriage is bodily movable toward and from the inking roller and is swingingly mounted at one end, said carriage being free to rise and fall at its opposite end as it is bodily moved; 120 and a guiding support for guiding the carriage in its bodily movement in the absence of the inking roller.

5. A printing press having an inking roller for the printing surface of the press; 130

adjacent to said pinion, the rack having a curved portion that forces the elevation of the pinion end of the carriage away from the inking roller when the carriage is bodily moved from the inking roller.

12. A printing press having an inking roller for the printing surface of the press; a distributing roller for contacting with the inking roller; a carriage in which the distributing roller is mounted and which carriage is bodily movable toward and from the inking roller; a carriage in which the dis-
10 carriage; a rack with which the pinion meshes, said rack and pinion being arranged transversely with respect to the rollers; means whereby said pinion is turned to cause the carriage to be moved bodily toward and from the inking roller, said carriage being also swingingly mounted adjacent to said pinion, the rack having a curved portion that forces the elevation of the pinion end of the carriage away from the inking roller when the carriage is bodily moved from the inking roller; and means for keeping the pinion and rack in mesh.

13. A printing press having an inking roller for the printing surface of the press; a distributing roller for contacting with the inking roller; a carriage in which the distributing roller is mounted; a driven pinion provided upon the carriage; and a rack with which the pinion meshes, said rack and pinion being arranged transversely with respect to the rollers to enable the carriage to be moved bodily toward and from the inking roller, said carriage being free to rise and fall as it is bodily moved, the distributing roller being permitted to rise and fall when riding over the inking roller.

14. A printing press having an inking roller for the printing surface of the press; a distributing roller for contacting with the inking roller; a carriage in which the distributing roller is mounted; a driven pinion provided upon the carriage; a rack with which the pinion meshes, said rack and pinion being arranged transversely with respect to the rollers to enable the carriage to be moved bodily toward and from the inking roller, said carriage being also swingingly mounted adjacent said pinion, there being means whereby the pinion end of the carriage is elevated when the carriage is moved away from the inking roller and is depressed when the distributing roller is being brought into contact with the inking roller.

15. A printing press having an inking roller for the printing surface of the press; a distributing roller for contacting with the inking roller; a carriage in which the distributing roller is mounted; a driven pinion provided upon the carriage; and a rack with which the pinion meshes, said rack and pinion being arranged transversely with re-

spect to the rollers to enable the carriage to be moved bodily toward and from the inking roller, said carriage being also swingingly mounted adjacent to said pinion, the rack having a curved portion that forces the elevation of the pinion end of the carriage away from the inking roller when the carriage is bodily moved from the inking roller.

16. A printing press having an inking roller for the printing surface of the press; a distributing roller for contacting with the inking roller; a carriage in which the distributing roller is mounted; a driven pinion provided upon the carriage; a rack with which the pinion meshes, said rack and pinion being arranged transversely with respect to the rollers to enable the carriage to be moved bodily toward and from the inking roller, said carriage being also swingingly mounted adjacent to said pinion, the rack having a curved portion that forces the elevation of the pinion end of the carriage away from the inking roller when the carriage is bodily moved from the inking roller; and means for keeping the pinion and rack in mesh.

17. A printing press having inking rollers for the printing surface of the press; a distributing roller for contacting with the inking rollers; and a carriage in which the distributing roller is mounted and which carriage is bodily movable, in a generally horizontal direction, toward and from the inking rollers in passing the distributing roller over the inking rollers, said carriage being free to rise and fall as the distributing roller rides over the inking rollers whereby the distributing roller is permitted to rise and fall when riding over an inking roller.

18. A printing press having inking rollers for the printing surface of the press; a distributing roller for contacting with the inking rollers; and a carriage in which the distributing roller is mounted and which carriage is bodily movable, in a generally horizontal direction, toward and from the inking rollers in passing the distributing roller over the inking rollers, the distributing roller being free to rise and fall as it rides over the inking rollers.

19. A printing press having inking rollers for the printing surface of the press; a distributing roller for contacting with the inking rollers; and a swingingly mounted carriage having a free or unmounted end and in which the distributing roller is mounted and which carriage is bodily movable, in a generally horizontal direction, toward and from the inking rollers in passing the distributing roller over the inking rollers, said carriage being free to rise and fall, at its unmounted end, as the distributing roller rides over the inking rollers.

20. A printing press having inking rollers

for the printing surface of the press; a distributing roller adapted to coöperate with the inking rollers; and a carriage in which the distributing roller is mounted, said carriage being bodily movable toward and from the inking rollers and swingingly mounted at one end to be free to rise and fall at its opposite end as it is bodily moved whereby the distributing roller is permitted to

rise and fall when riding over an inking roller.

In witness whereof, I hereunto subscribe my name this 9th day of December A. D., 1911.

ROBERT MIEHLE.
